UNITED STATES PATENT OFFICE.

JOSEPH ENZER, HARRISON H. GIFFORD, AND JOSEPH PRESNER, OF MONTREAL, QUEBEC, CANADA, ASSIGNEES, BY DIRECT AND MESNE ASSIGNMENTS, OF ONE-THIRD TO SAID ENZER, ONE-THIRD TO SAID PRESNER, AND ONE-THIRD TO GERALD S. TRITT, OF MONTREAL, QUEBEC, CANADA.

TOILET ARTICLE.

Refiled for abandoned application Serial No. 486,647, filed July 1, 1921. This application filed April 24, 1924. Serial No. 703,705.

To all whom it may concern:

Be it known that we, JOSEPH ENZER, HARRISON H. GIFFORD, and JOSEPH PRESNER, all of the city of Montreal, Province of Quebec, 5 Dominion of Canada, subjects of the King of Great Britain, have invented certain new and useful Improvements in Toilet Articles; and we do hereby declare that the following is a full, clear, and exact description 10 thereof.

This application is refiled for the abandoned application No. 486,647, filed July 1, 1921.

Our invention relates particularly to articles to be employed for cleaning the teeth and has for its object to provide a compact and sanitary tooth cleaning kit which may be carried in one's vest pocket and which will be ready for instant use.

20 A further object of the invention is to provide a simplified construction and arrangement of parts which may be assembled as a unitary member of neat appearance and which may be manufactured at a comparatively low cost.

25 A feature of the invention is a case or container a portion of which constitutes the handle or part of the handle of the tooth brush, the bristles being detachable as a unit from the handle. Another feature of the invention is means for preventing the bristles spreading. Another feature of the invention is a receptacle for tooth paste the interior of which may be readily exposed 30 for filling and cleaning and having means for discharging the paste therefrom. Other minor features which lie in the combination, construction and particular arrangement of the parts are hereinafter set forth in the 35 detail description.

40 For full comprehension, however, of our invention reference must be had to the accompanying drawings in which similar reference characters indicate the same parts and wherein:

Figure 1 is a side elevation of our improved tooth cleaning kit assembled;

Figure 2 is a longitudinal sectional view taken on line 2—2 Figure 1;

50 Figures 3, 4 and 5 are transverse sectional views taken on lines 3—3, 4—4 and 5—5 respectively, of Fig. 2;

Figure 6 is a plan view of the tooth brush;

Figure 7 is a transverse sectional view taken on line 7—7 Figure 6;

55

Figures 8 and 9 are detail views of the 60 sliding closure for the tooth paste receptacle;

Figure 10 is a detail plan view of the case; and

65

Figures 11 and 12 illustrate a modification.

The construction and arrangement of parts illustrated in the drawing and herein-after described constitute the preferred embodiments of our invention and we wish it to be clearly understood that we do not confine the invention to these specific constructions.

The embodiment illustrated in Figures 1 and 10 inclusive consists of a box-like case or container 2 of oblong form of a length substantially the same as that of the ordinary tooth brush although the size and shape of the case may be varied to meet requirements. The case is constituted by longitudinal side walls 3, 4, 5 and 6; end walls 7 and 8 and a cap 9. The wall 6 is removable from the body of the case and performs the dual function of a handle for a tooth brush the bristles of which are indicated at 10, and a cover which when removed permits access to a tooth paste chamber or receptacle 12 and means for discharging the paste therefrom which will be presently described.

70

The tooth brush when in assembled position is located with the bristles 10 positioned in a chamber 13 at one end of the case and with the opposite end of the handle bearing flat against a slide 16 constituting a removable closure for the tooth paste receptacle. The brush is retained in this position by a spring clip 14 on the end of the case adjacent the bristles and at the opposite end the handle of the brush abuts against a shoulder 17 on the case and the case and handle are reduced as at 18 to accommodate the cap 9 which overlaps the brush handle and closes the discharge opening 20 of the paste 80 receptacle 12. The cap and case are provided with air vents 21 and 22 respectively, the latter communicating with the chamber 13.

85

The tooth brush when in assembled position is located with the bristles 10 positioned in a chamber 13 at one end of the case and with the opposite end of the handle bearing flat against a slide 16 constituting a removable closure for the tooth paste receptacle. The brush is retained in this position by a spring clip 14 on the end of the case adjacent the bristles and at the opposite end the handle of the brush abuts against a shoulder 17 on the case and the case and handle are reduced as at 18 to accommodate the cap 9 which overlaps the brush handle and closes the discharge opening 20 of the paste 90 receptacle 12. The cap and case are provided with air vents 21 and 22 respectively, the latter communicating with the chamber 13.

90

In order to replace the bristles when worn 105 out they are mounted in a slide 30 which is

detachably seated in a slideway 31 in the handle, a spring detent 32 being adapted to prevent displacement of the slide therefrom.

The tooth paste receptacle is located at 5 the end of the case opposite to that accommodating the bristles and extends from a point substantially midway the length of the case to the end 8 thereof when it terminates in a tapered discharge opening 20 hereinbefore mentioned.

To enable the receptacle to be easily cleaned and filled the side thereof adjacent the handle of the brush is constituted by the slide 16. The latter consists of a flat strip 15 of increased thickness at its inner end as at 40 and grooved as at 41 to register with inwardly projecting tongues 42 on the adjacent portions of the case, the tongues and grooves being comparatively short to allow 20 the side to be removed by a slight longitudinal movement. The side edges of the latter are adapted to be seated on shoulders 43 on the walls 3 and 4 of the case while its outer end projects into a notch 44 in the 25 shoulder 17.

The means for discharging the paste through the opening 20 consists of a plunger 50, the stem of which is provided with a finger hold 51 and slides in a channel 52 in an inward projection 53 on the wall 5 of the case, lateral displacement of the plunger from the channel being prevented by the end 40 of the slide 16.

The foregoing construction and arrangement of parts provides a kit having a neat exterior which may be carried in one's vest pocket and which may be readily dismembered. Those which are designed to be carried in the vest pocket may be provided 40 with the usual pocket clip 60.

Figures 11 and 12 illustrate a modification of our invention designed to meet a requirement for a kit in which the tooth paste receptacle with the plunger is eliminated.

45 This modified construction consists of a case 70 constituted by side walls 71, 72, 73 and 74 respectively, end walls 75 and 76 and cap 77. The wall 74 forms half the handle for the brush 78, the case forming the other half. When it is desired to use the brush 50 the latter which is retained in position by a spring clip 79 and the cap 77 is removed from the case and the end 80 of the handle 55 is seated in a socket 81 in the end wall 76 of the case in the position indicated in dotted lines in Figure 11.

In order to prevent the bristles spreading when inserting the brush into the case an endless loop 90 is first placed in position encircling the bristles.

Where reference is made to tooth paste throughout the specification it is to be understood that all tooth cleansers are intended to be covered thereby.

65 What we claim is as follows:—

1. A tooth cleaning kit consisting of a hollow case having an open side, a receptacle for a tooth cleanser located within the case and a tooth brush adapted to be located within said case with its handle closing said side, said tooth brush being separate and distinct from the case and constructed and arranged to be completely disconnected therefrom when in use. 70

2. A tooth cleaning kit consisting of a hollow case having an open side and containing a receptacle for tooth cleanser, a removable closure for said receptacle, means for discharging the cleanser from said receptacle, said last mentioned means and the closure being accessible through said open side, and a removable tooth brush adapted to be located within the case with its handle closing said open side. 75

3. A tooth cleaning kit comprising a case having at one end a receptacle with a discharge opening for a tooth cleanser, a removable brush located within said case with the bristles positioned at the opposite end thereof and with its handle disposed parallel to and overlapping the receptacle and constituting a part of the case, and means for closing said discharge opening and retaining the brush in position. 80

4. A tooth cleaning kit comprising a case having a receptacle for tooth cleanser at one end with a discharge opening, a removable brush located within said case with the bristles positioned at the opposite end thereof and with its handle disposed parallel to and overlapping the receptacle, and means for closing said discharge opening and retaining the brush in position. 85

5. A tooth cleaning kit comprising a case having an open side and containing at one end a receptacle for a tooth cleanser, a removable brush located within said case with its bristles located at the opposite end thereof and with its handle closing said open side and means located at opposite ends of the case for retaining the brush in position. 90

6. A tooth cleaning kit comprising a case having an open side and containing at one end a receptacle with discharge opening for a tooth cleanser, a removable brush located within said case with its bristles located at the opposite end thereof and with its handle closing said open side and means located at opposite ends of the case for retaining the brush in position, one of said means consisting of a cap adapted to close said discharge opening. 95

7. A tooth cleaning kit comprising a case having an open side and containing at one end a receptacle with discharge opening for a tooth cleanser, a removable brush located within said case with its bristles located at the opposite end thereof and with its handle closing said open side, a spring clip adapted to secure one end of the brush 100

to the adjacent end of the case and a cap adapted to secure the opposite end of the brush to the adjacent end of the case, said cap constituting a closure for the discharge 5 opening of the receptacle.

8. A tooth cleaning kit comprising a case having an open side containing a receptacle for tooth paste at one end having a discharge opening, one side of said receptacle 10 being constituted by a removable slide accessible through the open side of the case, a removable tooth brush located in the case with its bristles located at the end thereof opposite to that containing the receptacle 15 and with its handle closing said open side and overlapping the said slide, and a plunger for discharging the paste from the receptacle said plunger being slidably mounted in the case between the bristles 20 and receptacle and projecting into the latter, and means located at opposite ends of the case for retaining the brush in position.

9. A tooth cleaning kit comprising a case having an open side containing a receptacle 25 for tooth paste at one end having a discharge opening, one side of said receptacle being constituted by a removable slide accessible through the open side of the case, a removable tooth brush located in the case 30 with its bristles located at the end thereof opposite to that containing the receptacle and with its handle closing said open side and overlapping the said slide, and a plunger 35 for discharging the paste from the receptacle, said plunger being slidably mounted in the case between the bristles and receptacle and projecting into the latter, and means located at opposite ends of the case 40 for retaining the brush in position, said last mentioned means consisting of a spring clip at one end of the case and a removable cap at the other, the cap constituting a closure for said discharge opening.

10. A tooth cleaning kit comprising a 45 case having an open side containing a receptacle for tooth paste at one end having a discharge opening, one side of said receptacle being constituted by a removable slide accessible through the open side of the case, a removable tooth brush located in the case with its bristles located at the 50 end thereof opposite to that containing the receptacle and with its handle closing said

open side and overlapping the said slide, and a plunger for discharging the paste 55 from the receptacle, said plunger being slidably mounted in the case between the bristles and receptacle and projecting into the latter, and means located at opposite ends of the case for retaining the brush 60 in position, said last mentioned means consisting of a spring clip at one end of the case and a removable cap at the other, the cap constituting a closure for said discharge opening and means upon the case for securing the same to an article of clothing. 65

11. A toilet article of the type described consisting of a hollow case having an open side and a tooth brush adapted to be mounted in the case in position closing said side, 70 said tooth brush consisting of a unitary member completely separable from the case when in use and equal in length to the length of the opening in said open side and a brush mounted on one end of the member. 75

12. A toilet article of the type described consisting of a hollow case having an open side and a tooth brush adapted to be mounted in the case in position closing said side, 80 said tooth brush being separate and distinct from the case and completely separable therefrom when in use and consisting of a unitary handle equal in length to the length of the open side, and a brush detachably mounted upon the handle. 85

13. A toilet article of the type described consisting of a hollow case having an open side and a tooth brush adapted to be mounted in the case in position closing said side, 90 said tooth brush consisting of a unitary handle equal in length to the length of the open side and having a slideway, and a brush consisting of a slide with bristles, slidably and detachably mounted in the slideway, and means for retaining the slide 95 in position in the slideway.

In testimony whereof we have signed our names to this specification in the presence of two witnesses.
